HEADBOARD OF A BED

Raul Z. Zamora, 562 University Ave.,
San Jose, Calif. 95110

Filed June 3, 1970, Ser. No. 23,265

Term of patent 14 years

Int. Cl. D6—01

U.S. Cl. D5—4

FIG. 2

FIG. 1 is a front perspective view of a headboard of a bed, showing my new design; and

FIG. 2 is a front elevational view thereof. The broken line fragmentary showing of a bed frame in FIG. 1 is for illustrative purposes only.

I claim:

The ornamental design for a headboard of a bed, substantially as shown and described.
